M. LADIN

TRIMMING FOR WEARING APPAREL

Filed Feb. 5, 1925

Inventor

Morris Ladin,

By Macon Fenwick Lawrence,
Attorney

UNITED STATES PATENT OFFICE.

MORRIS LADIN, OF BROOKLYN, NEW YORK.

DESIGN FOR TRIMMING FOR WEARING APPAREL.

Application filed February 5, 1925. Serial No. 12,273. Term of patent 7 years.

To all whom it may concern:

Be it known that I, MORRIS LADIN, a citizen of the United States, residing at Brooklyn, in the county of Kings and State of New York, have invented a new, original, and ornamental Design for Trimming for Wearing Apparel, as shown in the accompanying drawing and described in the following specification.

The drawing shows a face view of the new trimming for wearing apparel.

I claim:

The ornamental design for trimming for wearing apparel as shown.
